UNITED STATES PATENT OFFICE.

LEE J. VOORHEES, OF BINGHAMTON, NEW YORK, ASSIGNOR TO NATIONAL CARBON COMPANY, INC., A CORPORATION OF NEW YORK.

FLASH LIGHT.

Application filed March 29, 1922. Serial No. 547,882.

This invention relates to portable electric lamps, especially those of the type energized by a battery contained within a flat casing. The principal object of the invention is to provide improved means for retaining the battery cells in position.

In lamps of this type separate cells may be used, or a unitary battery may be prepared by packaging a plurality of cells and affixing suitable contact members. The first mentioned procedure is advantageous in that one or more of the cells may be replaced when necessary, without disturbing the others. Also, packaging adds materially to the cost of the battery. The present invention provides simple and reliable means for obtaining these and other advantages of the unit cell battery.

In general, the invention comprises a casing provided with resilient means for supporting a plurality of cells in laterally aligned relation, and means for series connecting the cells in a circuit including the lamp filament.

A preferred embodiment of the invention is illustrated in the accompanying drawings in which Fig. 1 is a front elevation of the lamp, the cover being in open position, and Fig. 2 is a vertical central section on line II-II of Fig. 1.

Referring to the drawings, 1 indicates a cup-shaped bottom section of a flat metal casing comprising a complementary cup-shaped cover section 2 hinged at 3. The embodiment of the invention which has been selected for illustration is intended for use as a pocket flashlight, and the casing is therefore rounded at its margin, so that it may fit conveniently into the pocket of the user. The dimensions and contour of the casing are adapted to the ordinary cylindrical flashlight cells. Any desired configuration of the casing may be chosen, however, with a view to the intended use of the lamp or the shape of the battery cells. A projection 4 is stamped in the side of casing 1 and snaps into depressible locking catch 5 when the cover 2 is closed.

A bulb holder 6 having a threaded stem 7 is mounted in a circular orifice in a bracket 8, which is attached to the casing in any suitable manner. The holder 6 is partly enclosed in a semicircular recess 9, and a corresponding indentation 10 in the end wall of cover 2 receives the projecting portion of the holder.

The exterior rim of holder 6 is preferably substantially flush with the casing. A lamp bulb 11 is screwed into the threaded stem 7 and its outer terminal is in electrical contact with the stem. The inner lamp terminal 12 projects below the holder 6. This terminal makes contact with a conductive tubular rivet 13 carried by a dished perforated tongue 14, preferably of resilient metal and forming an integral part of bracket 8.

Tongue 14 is electrically connected to the casing. To insulate the rivet 13 from the tongue, the perforation in the latter is made of such diameter as to leave an ample clearance for the rivet. This clearance and insulation are maintained by a fiber ring 15 set in the dished upper surface of the tongue 14 and a second similar ring 16 placed beneath it. The rings are clamped in position upon the tongue by expanding the ends of the rivet upon them, as shown in Fig. 2.

The means for removably supporting the cells comprises upper and lower resilient arms 17, 17' and 18, 18', arranged in pairs in vertical alinement. The upper arms 17, 18, may be conveniently formed integrally with bracket 8. Arms 17', 18', are substantially perpendicular projections from an arched metal strip 19, which extends along the medial line of the casing toward the lamp. This strip is suitably secured to the casing, by soldering or the like, with its concavity adjacent the casing bottom. In this manner a conduit is formed for insulated wires 20 and 21, which connect the cells in series, as subsequently described.

The resilient arms 17, 17', 18, 18', like the tongue 14, are provided with a central perforation and a concave upper surface. Tubular conductive rivets 22, 23, 24, 25, are passed through the perforations of arms 17, 17', 18, 18', respectively. Fiber rings 15' and 16' are clamped in place, as previously described, to insulate the rivets from the arms. Wire 20 connects rivets 23 and 24, and wire 21 connects rivets 25 and 13.

Cells 26 and 27, having the usual paper wrapper or other lateral insulation, are received between the arms 17, 17' and 18, 18', whereby the two cells are supported side by side in upright position between the pairs of resilient arms. Their carbon poles are in electrical contact with rivets 22 and 24 and their zinc bases rest upon rivets 23 and 25.

25. As the dimensions of the closed case are such that no undue freedom of motion is allowed the cells, and as the rivets are pressed against the electrodes by the resilience of the arms, good electrical contact is permanently assured.

10 A switch contact member 28, electrically connected to the casing, is adapted to engage tubular rivet 22. In the form of the invention illustrated, the contact member is operated by a simple slide mechanism 29, but other forms of switch may obviously be substituted.

15 The electrical circuit is as follows: Through cell 26 to rivet 23, thence through wire 20 to rivet 24 and cell 27, thence through rivet 25 and wire 21 to rivet 13 and the inner terminal of the lamp, through the filament of the lamp to its outer terminal, the holder 6, the casing and the switch, finally through the switch to rivet 22.

20 A metal casing has been described, but it will be understood that features of the invention are applicable as well to non-conductive casings. The number of cells 25 may also be varied as desired. Various other changes may be made in form and arrangement of parts, within the scope of the appended claims.

30 I claim:

1. In a portable battery-operated electric lamp, the combination of an incandescent lamp, a casing carrying said lamp, a plurality of separate electric cells, and means 35 permanently secured in said casing for supporting said cells upright in side by side relation within said casing and for connecting said cells in series circuit with one another and said lamp, said means comprising upper and lower resilient members extending inwardly from the lateral wall of a casing and adapted to receive said cells similarly inserted therebetween.

40 2. In a portable battery operated electric lamp, the combination of a casing, an incandescent lamp, separate cells connected in series and in circuit with said lamp, and means for retaining said cells upright in side by side relation in said casing comprising alined members, secured to and extending inwardly from a wall of said casing and carrying contacts engaging the poles of said cells, said alined members being permanently secured to a side wall of said casing 55 and relatively yieldable so they may be spread apart for the insertion and removal of cells.

60 3. In a portable battery-operated electric lamp, the combination of a casing, an incandescent lamp carried thereby, separate cells, means for retaining said cells in said casing comprising alined members secured to a wall of said casing and carrying contacts engaging the poles of said cells, a conduit within said casing, and wires passing

through but insulated from said conduit and electrically connecting certain of said contacts, so as to connect said cells in series circuit with said lamp.

4. In a portable battery-operated electric lamp, the combination of complementary cup-shaped casing sections, an incandescent lamp carried by one of said sections, a plurality of separate electric cells, and means secured in one of said sections for supporting said cells in side by side relation and electrically connecting them in series with one another and said lamp within the casing formed when such sections are closed together.

5. A portable battery operated electric lamp comprising a metal casing, a lamp bulb mounted therein, spring tongues adjacent the top and bottom of said casing and having metallic connections therewith, said tongues receiving a plurality of single cells therebetween, insulated conductive members carried by said tongues and adapted to make contact with the poles of the cells, and means for establishing an electrical circuit comprising the cells, the casing, and the filament of the lamp.

6. In a portable battery operated electric lamp; the combination of a casing; an incandescent lamp; separate cells; and means in said casing connecting said cells in series and in circuit with said lamp, comprising a bracket mounted on a side wall of said casing carrying contacts for like poles of said cells and a contact for said lamp.

7. In a portable battery operated electric lamp; the combination of a casing; an incandescent lamp; separate cells; and means for supporting said cells upright in said casing and connecting them in series and in circuit with said lamp, comprising means extending inwardly from a side wall of said casing carrying a contact for said lamp and contacts for the poles at the ends of said cells.

8. The invention according to claim 10, in which said lamp contact and one of the other contacts are insulated from the means carrying them.

9. In a portable battery-operated electric lamp, the combination of a casing comprising complementary cup-shaped sections, an incandescent lamp carried by one of said sections, a plurality of separate electric cells, and cell-supporting and connecting means 115 permanently secured in one of said sections, said means comprising resilient contacts engaging the opposite poles of said cells to support said cells upright in side by side relation and connecting said cells in series 120 circuit with one another and said lamp.

10. In a portable battery-operated electric lamp, the combination of a casing, an incandescent lamp carried thereby, a plurality of separate electric cells, means for 130

supporting said cells in side by side relation in said casing comprising a pair of upper arms and a pair of lower arms, said pairs of arms being permanently secured to an inner side wall of said casing and spaced apart to receive said cells therebetween, said arms engaging the ends of said cells to retain them.

11. In a portable battery-operated electric lamp, the combination of a casing; an in-

candescent lamp carried thereby; a plurality 10 of separate cells; spaced pairs of arms engaging the ends of said cells and supporting them in side by side relation in said casing and means extending medially of said casing to connect said cells in series circuit with one 15 another.

In testimony whereof, I affix my signature.

LEE J. VOORHEES.
